UNITED STATES PATENT OFFICE.

JAMES S. RAIRDEN, OF WATERFORD, CALIFORNIA.

FLY SWATTER.

Application filed June 12, 1923. Serial No. 644,926.

To all whom it may concern:

Be it known that I, JAMES S. RAIRDEN, a citizen of the United States, residing at Waterford, in the county of Stanislaus and 5 State of California, have invented certain new and useful Improvements in Fly Swatters of which the following is a specification.

My invention relates to a fly swatter, and the main object is to provide a swatter that 10 will stand a great deal more hard usage than swatters now found on the market.

The common manner of securing the wire mesh to the handle of the swatter is to rigidly attach it to the same, consequently for 15 every blow to the swatter, the wire mesh is bent along the edge of the handle where it is attached and in a short time, the mesh will break at this place and the swatter will be useless.

20 In the swatter forming the subject matter of the present invention, a double screen is provided, which is only slightly exposed to bending and especially not along the straight portion of the handle to which 25 it is attached. Instead, the screen is hinged to the handle and held in extended or inactive position by springs. The latter will yield to one side or the other when a blow is given with the swatter, so that no unnecessary strain is communicated to the screen.

30 In the accompanying drawing,

Figure 1 shows a side elevation of the preferred construction of the swatter;

35 Figure 2 is a fragmentary section along line 2—2 of Figure 1; and

Figure 3 is a fragmentary perspective view showing a slightly modified form of the swatter.

40 Referring particularly to Figures 1 and 2 of the drawing, reference numeral 10 represents the handle which is preferably made of wire and consists of two lengths of half-round wire 11 and 12 placed with their flat sides together along line 13. The head of 45 the handle is formed by two loops 14 bent outwardly in opposite directions from the handle proper to form a T therewith, and the straight outer portion 15 of the T constitutes the hinge rod for the screen.

50 About the middle of the handle shank, the wires are twisted around each other as at 16 to strengthen and stiffen the handle, and the extreme ends of the wires are preferably twisted together as at 17 to firmly connect 55 them at this end.

In Figure 2 is shown a coil spring 18,

which is wound around the straight outer portion of the handle serving as the hinge rod 15. One end of the spring 18 is inserted between the two half-round wires 12 and 11, 60 forming the hinge rod, and the other end of the spring extends radially therefrom to form an upstanding arm 19 arranged to extend in longitudinal direction of the handle, as seen in the figures. Several of these 65 springs 18 are assembled in the same manner as has just been described with regard to the hinge bar, but preferably in such a manner that the arm 19 of one spring extends from the last coil on one side of the hinge 70 rod, while the arm 19 of the next spring extends from a coil on the other side of the rod.

The swatting plane consists of two layers of wire mesh 20 doubled up around the 75 hinge rod 15 in such a manner that the springs 18 are surrounded by the wire mesh and the shanks or arms 19 are situated between the two layers beyond the hinge rod 15. The screen is held firmly to the shanks 80 or arms 19 of the springs by means of staples 21, or by stitching which may also continue around the edges of the wire mesh to hold the two layers together.

In Figure 3 of the drawing, a slightly 85 modified form of the invention is illustrated, and the handle 22 is constructed as before, of two half-round wires, which, however, at the T portion thereof are provided with a pair of loops 23 one at each end, in which 90 loops a hinge rod 24 is inserted and held from turning. This hinge rod 24 is also made of two half-round pieces of wire so that the springs engage with their short shanks between the flat sides of the hinge 95 rod 24, while the long shanks engage between the two layers of wire mesh, as already described.

When applying a blow, the swatter plane will yield along the hinge rod 15, when half 100 of the springs 18 will be coiled up, while the other half of them will uncoil; and the opposite will take place when the other side of the swatter is used, so that the springs actually work in opposition to each 105 other, but all of them tending to return the swatter plane into extended position, as indicated in the drawings.

Having thus described the invention, what is claimed as new is:

110 1. A swatter comprising a handle and a swatting plane; said handle having a T

portion upon which the swatter plane is hinged, and means for yieldingly holding the plane in extended position with regard to the handle, said plane including a double 5 layer of wire mesh, doubled around said T portion.

2. A swatter comprising a handle and a swatting plane; said handle having a T portion upon which the swatter plane is hinged, and means for yieldingly holding the plane in extended position with regard 10 to the handle, said handle being formed by two pieces of half-round wire placed with their flat sides together, said wires being 15 twisted around each other medially between its ends.

3. A swatter comprising a handle and a swatting plane; said handle having a T portion upon which the swatter plane is hinged, and means for yieldingly holding the plane in extended position with regard 20 to the handle, said handle being formed by two pieces of half-round wire placed with their flat sides together, said wires being 25 twisted around each other medially between its ends, and said yieldable means including coil 30 springs around said T portion of the handle, each of said springs having one shank inserted between the flat faces of the wire pieces and the other end secured to the swatting plane.

4. A swatter comprising a handle and a

swatting plane; said handle having a T portion upon which the swatter plane is hinged, and means for yieldingly holding the plane in extended position with regard 25 to the handle, said plane including a double layer of wire mesh, doubled around said T portion, said handle being formed by two pieces of half-round wire placed with their 30 flat sides together, and said wires being twisted around each other medially between its ends.

5. A swatter comprising a handle and a swatting plane; said handle having a T portion upon which the swatter plane is hinged, and means for yieldingly holding the plane in extended position with regard 40 to the handle, said plane including a double layer of wire mesh, doubled around said T portion, said handle being formed by two pieces of half-round wire placed with their 45 flat sides together, said wires being twisted around each other medially between its ends, and said yieldable means including coil 50 springs around said T portion of the handle, each of said springs having one shank inserted between the flat faces of the wire pieces and the other end secured to the 55 swatting plane.

In testimony whereof I affix my signature.

JAMES S. RAIRDEN. [L.S.]
